(57) **CLAIM**

The ornamental design for a universal ground fault circuit interrupter (GFCI) printed circuit board package, as shown and described.

DESCRIPTION

FIG. 1 is a top perspective view of a universal ground fault circuit interrupter (GFCI) printed circuit board package showing our new design;

FIG. 2 is a top view thereof;

FIG. 3 is a bottom view thereof;

FIG. 4 is a left side view thereof;

FIG. 5 is a right side view thereof;

FIG. 6 is a rear elevation view thereof;

FIG. 7 is a front elevation view thereof;

FIG. 8 right side view thereof shown in a used condition with a right angle GFCI enclosure shown in broken lines; and,

FIG. 9 is another right side view thereof shown in a used condition with an inline GFCI enclosure shown in broken lines.

The broken lines of FIGS. 8 and 9 of a right angle and inline GFCI enclosures and the broken lines in FIGS. 1-5 and 7 of power input terminals form no part of the claimed design.
